UNITED STATES PATENT OFFICE.

WILLIAM M. JORDAN AND CHARLES S. NICHOLS, OF LINCOLN, NEBRASKA.

CORN SHELLER.

Application filed December 22, 1924. Serial No. 757,531.

This invention relates to corn shellers and more particularly to the cylinder and concave thereof.

Briefly stated, an important object of this invention is to provide a corn sheller having novel means to adjust itself to ears of various sizes.

A further object of the invention is to provide a corn sheller having a cylinder provided with separate blades having their outer faces disposed tangentially with respect to the periphery of the cylinder to define an annular series of gradually tapering pockets for the reception of the corn whereby to bring about the rapid and more perfect operation of the sheller.

A further object of the invention is to provide a corn sheller which is of highly simplified construction, durable in use, and cheap to manufacture.

Other objects and advantages will be apparent during the course of the following description.

In the accompanying drawings forming a part of this application and in which like numerals are employed to designate like parts throughout the same,

Fig. 1 is a vertical sectional view through the improved cylinder and concave;

Fig. 2 is a detail side elevation illustrating the means to operate the cylinder;

Fig. 3 is a longitudinal sectional view through the cylinder;

Fig. 4 is a group perspective illustrating the cylinder and one of the blades.

In the drawings, wherein for the purpose of illustration is shown a preferred embodiment of the invention, the numeral 5 designates the concave of the improved corn sheller, the concave being provided with end plates or walls 6. Slats 9 are arranged in spaced arcual series and bolted as indicated at 7, to or adjacent the curved edges of walls 6. The mode of application of slats 9 is relatively unimportant and they may be secured in grooves in walls 6 or in other conventional ways well known in the art. Fig. 1 illustrates that the slats 9 are arranged in spaced parallel relation to define passages for the corn during the shelling operation.

It will be seen that the end walls 6 are provided with grooves 10 for the reception of hangers 11 having abutments 11^a at their upper ends, the lower portions of said hangers 55 being extended angularly as indicated at 12 to anchor the hangers to the end walls 6.

That is to say, the lower portions of the hangers 11 are extended laterally through the end walls 6 to firmly attach the hangers to the concave. Figure 1 also shows the inner surfaces of the opposed side walls W of the machine as provided with companion grooves W' which receive the opposite sides of hangers 11. As will be readily apparent, the two opposed sets of grooves 10 and W' co- 65 operate with hangers 11 to prevent the same from swinging and yet permit of a vertical sliding movement. Thus, the concave 5 is adjustable in a vertical direction only.

Fig. 1 illustrates that the hangers 11 extend above the concave and pass through supporting springs 14 resting upon the upper edges of side walls W of the machine, the springs forming a means to yieldably support the concave. That is to say, the 75 springs are mounted on the upper terminal portions of the hangers 11 and normally maintain the concave in a fixed position. However, to provide for shelling corn of various sizes the springs will yield and there- 80 by allow the concave to move up or down as the occasion requires. The tension of the springs 14 may be varied from time to time. Also the cooperating grooves 10 and W' prevent movement of rods 11 to disengage their springs 14 from the top edges of said walls W of the machine.

The cylinder is generally designated by the numeral 20 and is provided with end walls 22 having separate tangentially arranged flat faces 24 against which the attaching portions 26 of the blades 28 are secured by any suitable means as for instance by hooks 26^a. The blades 28 are separately secured to the flat faces 24 and any one or 95 all of the blades may be replaced from time to time. Fig. 4 illustrates that the outer faces of the blades 28 are formed with knobs 30 for aiding in the effective shelling of the corn.

Referring now to Fig. 1 it will be seen that the outer faces of the blades 28 are disposed tangentially to define a series of gradually deepening sockets or it might be said pockets which taper away from the direction of travel of the cylinder.

It will be seen that the hopper 40 discharges the corn directly onto the cylinder and thereby brings about the more rapid operation of the machine.

The shaft 20^a carrying the cylinder 20 is supported in outwardly extending bearings

B at either side of the machine, these bearings being carried by said walls W so that the cylinder 20 is always in a fixed horizontal position with relation to the ground. It can be seen from this description that when corn is introduced through the hopper 40 and is carried around by the projections 30 on the face of the cylinder any larger ears of corn will force the concave downwardly.

10 This downward movement is permitted through means of the springs 14 connected to the upper ends of the rod 11.

Having thus described the invention, what is claimed is:

15 1. In a corn sheller including a body portion and a fixedly journalled drum having a peripheral grinding surface; the combination of a concave partially surrounding said drum and having end walls and a material 20 receiving opening, rods secured to said concave and yieldingly supported by said body portion, and said concave and body portion having cooperating guide means engaging said rods to prevent swinging thereof and 25 to guide the same in a sliding movement.

2. In a corn sheller including a body portion and a fixedly journalled drum having a peripheral grinding surface; the combination of a concave partially surrounding said 30 drum and having end walls and a material receiving opening, rods secured to said concave and yieldingly supported by said body portion, and said concave and body portion having cooperating 35 guide grooves engaging said rods to prevent swinging thereof and to guide the same in a sliding movement.

3. In a corn sheller including a body portion and a fixedly journalled drum having a peripheral grinding surface; the combination of a concave partially surrounding said 40 drum and having end walls and a material receiving opening, depending hanger rods pivoted to said concave and yieldingly supported by said body portion, and said concave and body portion having cooperating 45 guide grooves engaging said rods to prevent swinging thereof and to guide the same in a sliding movement.

4. In a corn sheller including a body portion and a fixedly journalled drum having a peripheral grinding surface; the combination of a concave partially surrounding said 50 drum and having end walls and a material receiving opening, L-shaped hanger rods having their lateral ends engaging transversely into the opposed end walls of said concave, the upstanding ends of said hanger rods extending above the upper edge of said body portion and having abutments thereon, 55 springs interposed between said abutments 60

and the upper edge of said body portion for yieldingly supporting said hanger rods and the concave, and the opposed surfaces of the body portion and the end walls of said concave having guide means engaging said 65 hanger rods for slidably mounting the same for movement in a vertical direction and for preventing swinging thereof and the disengagement of said springs from the upper edge of said body portion.

5. In a corn sheller including a body portion and a fixedly journalled drum having a peripheral grinding surface; the combination of a concave partially surrounding said 70 drum and having end walls and a material receiving opening, upstanding hanger rods secured to said concave and having their upper ends extending above the upper edge of said body portion, abutments upon the upper ends of said hanger rods, springs surrounding said rods and interposed between said abutments and the upper edge of said body portion for yieldingly supporting said hanger rods and concave, and the opposed 75 surfaces of the body portion and the end walls of said concave having guide means engaging said hanger rods for slidably mounting the same for movement in a vertical direction, said guide means cooperating to prevent movement of said rods to disengage 80 said springs from the upper edges of said body portion.

6. In a corn sheller including a body portion and a fixedly journalled drum having a peripheral grinding surface; the combination of a concave partially surrounding said 85 drum and having end walls and a material receiving opening, upstanding hanger rods secured to said concave and having their upper ends extending above the upper edge of said body portion, abutments upon the upper ends of said hanger rods, springs surrounding said rods and interposed between said abutments and the upper edge of said body portion for yieldingly supporting said hanger rods and concave, the opposed inner 90 surfaces of said body portion having guide portions for assuring longitudinal sliding movement of said rods, and the opposed outer surfaces of the end walls of said concave engaging said rods to hold the same in operative engagement with said guide portions whereby to prevent disengagement of said springs from the upper edge portions of said body.

In testimony whereof we affix our signatures.

WILLIAM M. JORDAN.
CHARLES S. NICHOLS.
